MUSIC BOX TOY

John W. Ryan, Bel Air, Calif., assignor to Mattel, Inc., a corporation of California

Filed Jan. 20, 1966, Ser. No. 692

Term of patent 14 years

(Cl. D34—15)

FIG-1

Fig-5

FIG. 1 is a perspective view of a music box toy showing my new design;

FIG. 2 is a left-hand side elevational view looking in at the front of FIG. 1;

FIG. 3 is an end elevational view looking in at the rear of FIG. 1, the opposite end being the same;

FIG. 4 is a bottom view of the design; and

FIG. 5 is a top plan view of the design.

I claim:

The ornamental design for a music box toy, as shown and described.
